UNITED STATES PATENT OFFICE.

ALLEN EDWARD OSTRANDER, OF PATERSON, NEW JERSEY, ASSIGNOR TO AMERICAN CAR & FOUNDRY COMPANY, OF ST. LOUIS, MISSOURI, A CORPORATION OF NEW JERSEY.

CAR-TRUCK.

No. 846,240.

Specification of Letters Patent.

Patented March 5, 1907.

Application filed November 19, 1906. Serial No. 344,021.

To all whom it may concern:

Be it known that I, ALLEN EDWARD OSTRANDER, a citizen of the United States, residing at Paterson, New Jersey, have invented a certain new and useful Improvement in Car-Trucks, of which the following is a full, clear, and exact description, such as will enable others skilled in the art to which it appertains to make and use the same, reference being had to the accompanying drawings, forming part of this specification, in which—

Figure 1 is a plan view of a car-truck constructed in accordance with my invention. Fig. 2 is a side elevation of said truck, showing the preferred form of equalizing device. Fig. 2^a is an end view of a portion of the truck shown in Fig. 2. Fig. 3 is a side elevation of the truck, showing a modified form of equalizing device. Fig. 4 is a detail perspective view showing the manner of connecting the transversely-extending angles to the pedestal-tie-bar braces. Fig. 5 is a detail perspective view showing the manner of connecting the end piece and side frame of the truck together, and Fig. 6 is an enlarged transverse sectional view taken through the center of the truck.

This invention relates to car-trucks.

One object of my invention is to provide a car-truck in which the frame is constructed in a novel manner from commercially-rolled shapes, and another object of my invention is to provide a novel means for equalizing the bearing of the truck-frame on the journal-boxes.

Referring to the drawings, which represent the preferred form of my invention, 1 designates the side frames of the truck, which consist of I-beams, although channels could be used, if desired. The end pieces 2 of the truck-frame consist of angles arranged with their horizontal legs projecting inwardly and lying in the same plane as the top flanges of the side frames 1. As shown in Fig. 5, the horizontal leg of the end piece angle 2 is cut away, so that the vertical leg of said angle can butt against the web of the I-beam 1, and these two members are connected together by an L-shaped bracket 3 and by a gusset-plate 4, secured to the top flanges of said members,

the bracket 3 bearing upon the inner faces of said members.

The pedestals 5 are constructed at their upper ends to incase the bottom flanges of the I-beam side frames and are secured to the webs of said beams by rivets 6, which extend through vertical flanges 7 on the pedestals. Each pedestal-tie-bar brace is connected at its opposite ends to the side frame 1, and said braces preferably consist of a number of angles. The angle 8, which forms the central section of said brace, is secured at its opposite ends to the inner legs of the pedestals and is arranged with its horizontal leg projecting inwardly. The end sections of the pedestal-tie-bar brace consist of straight angles 9, arranged with their horizontal legs projecting inwardly and inclined angles 10, connected to the angles 9 by rivets 11 and arranged with their horizontal legs projecting outwardly, the angles 9 being connected to the outside legs of the pedestals and the angles 10 being bent at their upper ends to form horizontal portions which are connected to the bottom flanges of the I-beams 1. Short angles 12, arranged with their horizontal legs projecting outwardly, extend across the open ends of the pedestals and are detachably connected to the vertical legs of the angles 8 and 9 by means of bolts 13. By arranging the angles 12 and the angles 8 and 9 so that their horizontal legs project in opposite directions, a very wide bearing-base is provided for the lower ends of the pedestals and the journal-boxes 14, the legs of the pedestals being secured to the horizontal legs of the angles 8 and 9 by means of fastening devices, as indicated in Fig. 1. The tie-bar brace, on the opposite sides of the truck are connected together by means of transversely-extending angles 15, the horizontal legs of which project inwardly in the same plane as the horizontal legs of the angles 9, to which they are connected by gussets 16, said angles also being fastened together by L-shaped brackets 17, secured to the inner faces of the vertical legs of said angles, as shown in Fig. 5, the horizontal legs of the angles 15 being cut away to permit the ends of said angles to butt against the vertical legs of the angles 9.

At the center of the truck intermediate the

pedestals are two transversely-extending angles 18, which are secured at their opposite ends to the angles 8 by means of L-shaped brackets, (shown in dotted lines in Fig. 2,) the horizontal legs of the angles 18 also being cut away so that the ends of said angles can butt against the vertical legs of the angles 8. The bolster of the truck-frame preferably consists of two channels 19, arranged with their horizontal legs projecting in opposite directions and connected at their opposite ends by means of L-shaped brackets 20 to the webs of the I-beam side frames, the top flanges of the channels 19 lying in the same horizontal plane as the top flanges of the I-beams 1 and being cut away, as shown in Fig. 6, so that the ends of the webs of said channels can butt against the webs of the I-beams 1.

20 The top plate 21 of the bolster, to which the center and side bearings 22 and 23, respectively, are connected, is riveted to the top flanges of the channels 19 and also to the top flanges of the side frames 1, and triangular-shaped gusset-plates 24 are provided to further strengthen the connection between the bolster and side frames, said gusset-plates being riveted to the top flanges of the side frames and to the top flanges of the channel 19 and plate 21, upon which they are superimposed, as shown in Figs. 2 and 3. The bottom plate 25 of the bolster is riveted to the lower flanges of the channels 19, and at the center of the bolster are braces which consist of short channel-shaped pieces 26, arranged between the channels 19, to the webs of which they are riveted, as shown in dotted lines in Figs. 1 and 6.

40 The means for equalizing the bearing of the truck-frame on the journal-boxes consists of equalizer levers or bars 27, fulcrumed on the journal-boxes 14 and connected at their opposite ends by yielding means to the truck-frame.

45 In the preferred form of my invention, as shown in Fig. 2, the outer end of each equalizer-bar is provided with a spring-seat 28, which supports a coiled spring 29, having its upper end resting in a spring-seat 30, fastened to the side frame 1. The inner ends of the equalizer-bars on each side of the truck are connected, by means of links 31, to a semi-elliptical spring 32, mounted in a bearing 33, depending from the side frame 1, thereby 55 producing a very simple means for equalizing the bearing of the frame on the journal-boxes, said boxes being preferably provided with a rib 34, which enters a recess in the underneath side of the equalizer-bar to prevent it from shifting on the journal-box. By varying the position of the bearing 33, which acts as a fulcrum for the spring 32, to one side or the other of the center line the tractive power on either pair of wheels of the track 60 can be increased, as the change in location of

this fulcrum will tend to throw more weight on one pair or the other.

In the form shown in Fig. 3 the semi-elliptical spring 32 is replaced by a bar 35, provided at its opposite ends with seats 36, which receive coiled springs 37, that are supported by seats 38 on the inner ends of the bars 27, the inner ends of said bars preferably curving downwardly, as shown in Fig. 3.

Having thus described my invention, what I claim as new, and desire to secure by Letters Patent, is—

1. A car-truck comprising side frames having pedestals connected thereto, tie-bar braces connected at their opposite ends to the side frames and consisting of angles upon the horizontal legs of which the legs of the pedestals rest, and removable angles secured to the vertical legs of said angles for closing the lower ends of the pedestals; substantially as described.

2. A car-truck comprising side frames having pedestals connected thereto, pedestal-tie-bar braces consisting of straight angles arranged with their horizontal legs projecting inwardly, and inclined angles arranged with their horizontal legs projecting outwardly, and removable angles secured to the straight angles for closing the lower ends of the pedestals; substantially as described.

95 3. A car-truck comprising side frames having pedestals connected thereto, pedestal-tie-bar braces consisting of a plurality of angles connected together, and transversely-extending angles fastened to the tie-bar braces on opposite sides of the truck; substantially as described.

4. A car-truck having flanged side frames to which pedestals are secured, straight angles arranged with their horizontal legs projecting inwardly and fastened to said pedestals, inclined angles arranged with their horizontal legs projecting outwardly and secured at their lower ends to said straight angles and at their upper ends to the flanges of the side frames, and a transversely-extending angle connected to the straight angles on the opposite sides of the truck at the points where said angles are connected to the inclined angles, the horizontal leg of said transversely-extending angle being cut away to permit the ends of said angle to butt against the vertical legs of the straight angles; substantially as described.

105 5. A car-truck comprising a side frame having pedestals connected thereto, and a pedestal-tie-bar brace consisting of straight angles fastened to the pedestals, and inclined angles having their upper ends bent to extend parallel to the side frames to which they are fastened; substantially as described.

110 6. A car-truck comprising flanged side frames provided with pedestals for receiving journal-boxes, equalizer-bars adapted to rest on said journal-boxes, coiled springs inter- 130

posed between the outer ends of said bars and the side frames of the truck, depending 5 bearings supported by the lower flanges of the side frames, and members at each side of the truck fulcrumed on said bearings and connected at their opposite ends to the inner ends of the equalizer-bars, said depending bearings being adapted to be adjusted to one side or the other of the center line of the 10 truck to vary the tractive power on the wheels of the truck; substantially as described.

7. A truck comprising side frames provided with pedestals for receiving journal-boxes, equalizer-bars adapted to rest on said 15

journal-boxes, coiled springs interposed between the outer ends of said bars and the side frames, a bearing depending from each side frame, semi-elliptical springs fulcrumed on said bearings and links connecting the inner ends of the equalizer-bars to the opposite ends of said spring; substantially as described. 20

In testimony whereof I hereunto affix my signature, in the presence of two witnesses, 25 this 12th day of November, 1906.

ALLEN EDWARD OSTRANDER.
